UNITED STATES PATENT OFFICE

149,251

DESIGN FOR A COMBINED DISPLAY STAND
AND PERFUME BOTTLES

Victor Civita, New York, N. Y., assignor to Consolidated Cosmetics, Chicago, Ill., a firm

Application July 15, 1946, Serial No. 131,598

Term of patent 3½ years

(Cl. D80—9)

To all whom it may concern:

Be it known that I, Victor Civita, a citizen of the Republic of Italy, resident of New York, New York, have invented a new, original, and ornamental Design for a Combined Display Stand and Perfume Bottles, of which the following is a specification, reference being made to the accompanying drawings, forming a part thereof.

Referring now to the drawings, Fig. 1 is a top plan view of a combined display stand and perfume bottles embodying my new design; Fig. 2 is a side elevational view; Fig. 3 is a front elevational view; and Fig. 4 is an isometric view on a reduced scale of the same.

I claim:

The ornamental design for a combined display stand and perfume bottles, substantially as shown.

VICTOR CIVITA.
